AIR PISTOL

James P. Appleby, Anoka, Minn., assignor to The Federal Cartridge Corporation, Minneapolis, Minn., a corporation of Minnesota

Application October 14, 1937, Serial No. 168,918

4 Claims. (Cl. 124—15)

My present invention provides an extremely simple and highly efficient air gun of the type wherein the bullet or ball is projected under the combined action of a spring and compressed air. Particularly, the invention relates to such guns which, because of their comparatively short barrel and hand grip, are usually designated as "pistols" and are not usually provided with a shoulder rest but adapted to be held entirely in one hand. The device is, therefore, here entitled "Air pistol", but various novel features thereof are capable of incorporation more generally in portable gun structures.

Generally stated, the invention consists of the novel devices and combinations of devices herein-after described and defined in the claims.

A commercial form of the invention is illustrated in the accompanying drawings wherein like characters indicate like parts throughout the several views.

Referring to the drawings:

Fig. 1 is a side elevation showing the improved pistol;

Fig. 2 is an axial longitudinal section taken through the pistol shown in Fig. 1;

Figs. 3 and 4 are views corresponding to Fig. 2, but illustrating different positions of the movable parts of the device;

Fig. 5 is a perspective of a fixed bracket that serves to support the main spring and to guide the rear portion of the piston rod of the air mechanism;

Fig. 6 is a rear end elevation of the bracket shown in Fig. 5;

Fig. 7 is a perspective showing the cocking sear;

Fig. 8 is a perspective showing the inner or gun barrel proper, a feed hopper, and barrel head removed from the air cylinder or outer barrel;

Fig. 9 is a section taken on the line 9—9 of Fig. 3; and

Fig. 10 is a section taken on the line 10—10 of Fig. 3.

The frame of the pistol is preferably made from a single piece of sheet steel or similar metal stamped and bent to form a substantially cylindrical casing 11 and depending side plates 12, which latter are formed with a hand grip or handle 13 and with a finger loop 14. The side plates 12 have inturned edges that are clamped together by means of screws or rivets 15, 16 and 17. Slidable through the tubular portion 11 of the casing is a relatively long outer barrel 18 that affords an air cylinder. This outer barrel or cylinder 18, at the rear portion of its under side,

has a long slot 19 and onto its rear end is applied a barrel cap 20. This cap may be secured to the barrel 18 in various ways but, as shown, is thus secured by a stop plate 21 and a pin or screw 22, which latter is passed through the cap and barrel. The washer 21 at top and bottom is interlocked with slots in the barrel 18 and closes the rear end of the long slot 19 of said barrel 18.

Working within the cylinder-forming barrel 18 is a piston 23 having a plunger-acting rod 24. 10 As shown, the piston 23 is equipped with the ordinary leather cup 25 that insures an air-tight joint with the cylinder-forming barrel. At its rear end piston rod 24 is reduced to form a head or lock shoulder 26. This head 26, at the rear 15 end of the piston rod 24, works freely in but is guided by a tubular portion 27 of a bifurcated bracket 28 that is located within the frame just below the barrel 18 and is rigidly anchored by the screws or rivets 15 and 16, the detail construction 20 of which bracket is best shown in Fig. 5. This bracket and its sleeve afford a guide and base of reaction for a strong coiled main spring 29 that surrounds the piston rod 24 and reacts against the piston 23 with a force tending to impel the 25 latter and parts carried thereby violently forward when said spring is released, as will presently more fully appear.

When the piston and its rod are retracted, the head or shoulder 26 of said rod will be engaged 30 by the rear end of a cocking seat 30 that is intermediately pivoted on the screw or rivet 16. This sear, as shown, is a stamped metal structure best shown in detail in Fig. 7, and is channel-shaped and provided with an upturned rear end 35 terminating in a detent or flange 31 that is engageable with the shouldered head 26, when the latter has been forced rearward thereof. Also, it will be noted that the head 26 has a conical rear end or point which will have a cam action 40 to force down the rear end of sear 30 when the piston and rod are forced to extreme rearward position. Sear 30 is normally yieldingly held in the position shown in Fig. 1 by a coiled sear spring 32 anchored to the rivet 17 in the handle 45 13 at its lower end and having an upper end engaged around a cross bar 33 formed in the front portion of the sear.

For moving the sear to releasing position, there is provided a trigger 34 also preferably formed 50 from stamped sheet metal. This trigger is pivotally mounted on the rivet 15 and has a projecting L-shaped lug 35, the base of which is adapted to engage a cross bar 36 formed on the extreme front end of the sear. By reference to Fig. 2, 55

It will be noted that the extreme upper end of the lug 35 is just slightly below the bottom of the outer tube or air cylinder 18. In this position also it will be noted that the upper end of lug 35 is then slightly rearward of the extreme front end of slot 19 so that the trigger can then be pulled rearward, thereby causing the base of said lug to release the piston rod or plunger 24, when the parts are in the position shown in Fig. 4.

10 By reference to Fig. 3, however, it will be noted that when the outer barrel or cylinder 18 is drawn rearward the trigger will be locked by the then overlying portion of said tube 18 so that the piston rod can not then be released. These actions, 15 however, will be more clearly summed up in the description of the operation.

Rigidly secured in the intermediate portion of the barrel 18 is an annular barrel head 37 that is secured in position by indented portions 38 of barrel 18 pressed into the annular groove of said barrel. This barrel is thus fixed against both axial and rotary movements. Placed against the rear side of this barrel head is a pliable washer 39 that cushions the forward movement of the 25 piston.

The ball receiving inner barrel 40 is axially placed within the outer barrel 18 and is of such less diameter as to form an annular chamber 41 for the reception of balls, indicated by the character γ . This inner barrel 40, which constitutes the gun barrel proper at its rear end, is soldered or otherwise rigidly secured to a circumferential-grooved and flanged head 42 that is rotatably mounted in the barrel head 37. At the rear portion closely adjacent to the head 42 the barrel 40 is provided with a ball entering passage 43 and at a diametrically opposite point with a notch 44 that receives the bent end of a leaf spring 45, the front end of which is anchored to the bottom 40 of a trough-like hopper 46, see particularly Fig. 8, the front end of which is formed with an oblique deflecting flange 47. The feed hopper structure 38-37 is thus mounted to rotate with the gun barrel 40. At its extreme outer end the gun barrel 45 rel 40 is provided with a barrel cap 48 that is adapted to be engaged to rotate the barrel and parts carried therewith.

Rigidly secured to the piston 23 is a tubular ejector rod or pilot pin 49 that works with not loose but fairly close engagement through the axial passages of the washer 39, head 37, and barrel 40. This tubular rod or pin 49, close to the piston 23, is provided with one or more air ports 50.

55 The numeral 51 indicates a sight piece on top of the tubular portion 11 and the numeral 52 indicates a sight piece on the top of the front end of outer barrel 18. The barrel 18, at the front end of its lower portion, is provided with a ball entrance port 53 and the cylindrical portion of the barrel cap 48 is provided with a like ball entrance passage 54 and which passages function as hereinafter described.

It may be here noted that the base of the 60 bracket 28 projects through the slot 19 of the outer tube or barrel 18 and holds the latter against rotation but lays it free for longitudinal sliding movements between the positions shown in Figs. 2 and 3. The barrel cap 28 limits the 65 forward sliding movement of said outer barrel 18.

As above described, the sear 30, the trigger 34 and the guide sleeve 27 are all directly secured to the supporting bracket 28. Obviously, this permits the said parts to be operatively assembled in 70 proper adjustment at the factory before they are

applied in the gun. When this assembled unit is applied in the gun by securing of the bracket 28 to the casing the elements of the unit are thereby accurately assembled and accurately located in respect to the other parts of the gun. 75

Operation

Fig. 1 shows the positions of the movable parts of the device immediately after it has been fired. With the parts in the position shown in Fig. 2, 10 the entrance to the magazine 41 is closed. When, however, the barrel cap 48 with the parts attached thereto are rotated through 180°, the entrance ports or passages 53 and 54 will be aligned and the balls can then be inserted into the magazine 15 41. Obviously, a very large number of these balls can thus be inserted and stored up in the magazine ready for consecutive use. After the magazine has been filled more or less the cap 48 and parts thereon will be rotated back to the position shown in Fig. 2, thereby closing up the magazine. Whenever the piston or gun is pointed upward some of the balls will run down into the channel of the hopper 46 and the advanced ball will be lodged in the ball intake port 43. 25

When the cylinder-forming outer barrel 18 is forced to its extreme rearmost position, as shown in Fig. 3, the detent 31 of sear 30 will engage the head 26 of piston rod or plunger 24 and thereby lock the piston and pilot rod or firing pin 49 in the 30 retracted position, shown in Fig. 3.

When the outer barrel is moved rearward, as shown in Fig. 3, pilot pin 49 will still be projected into the inner or firing barrel 40, beyond the port 43. At this time the gun can not be fired because 35 the bottom of the outer barrel 18 overlies the lug 35 of the trigger, and hence, prevents the trigger from being pulled rearward or given its firing movement. Before the gun can be fired, the barrel 18 must be slid back to its normal position, 40 shown in Fig. 4. As the barrel 18 reaches its rearmost position the ball or bullet, partly entered in the port 43, will then fall in front of the pilot rod 49, where it will be held by the detaining spring 45 against rolling movement of the barrel 45 40. Thus, only one ball at a time can be entered into the firing barrel 40.

When the barrel 18 has been thus restored to its normal or forward position, the lug 35 of the trigger will be aligned with the slot 19 of the barrel 18 and rearward pressure on the trigger will then cause release of the piston and pilot rod, so that the main spring 29 will be released and will violently thrust the piston and rod 49 forward. Forward movement of these parts will, 50 under the action of the spring 29, produce two results, to wit: Air compressed in the barrel or cylinder 18, in front of the piston 23, will, under high pressure, be forced out through the tubular pilot 49 and discharged against the ball; and the 55 pilot pin 49 will be violently thrust against the aligned ball; so that the combined impact and blowing action will produce a high velocity discharge of the ball. Forward movement of the piston will be stopped and cushioned by the engagement thereof with the resilient washer 39. 60

This improved gun, whether in the form of a pistol or of a longer barreled or differently arranged gun, is capable of various modifications within the scope of the invention herein disclosed 70 and claimed. The pistol structure illustrated has, in actual practice, been found highly efficient for the purposes had in view.

What I claim is:

1. In a gun of the kind described, a casing, a 75

barrel slidably through said casing, ball-projecting means including a forwardly spring-pressed plunger working in said barrel and provided at its rear end with a sear-engaging detent, a bracket rigidly secured to said casing below said barrel and provided within said barrel with a tubular guide sleeve for the rear end of said plunger, a spring-pressed sear lever pivoted to said casing and having one end engageable with the detent of said plunger to hold the same retracted, a trigger pivoted within said casing and operative on said sear lever to release the same and produce the firing action, said trigger having an upwardly projecting lug operative on said sear lever, said barrel being cut away or removed at that portion thereof that overlies said trigger lug when said barrel is in the forward position, the lower uncut or removed body portion of said tube being arranged to overlie said lug and prevent firing when said barrel is in a rearward position.

2. In a gun of the kind described, a casing, a barrel slidably through said casing, ball-projecting means including a forwardly spring-pressed plunger working in said barrel and provided at its rear end with a sear-engaging detent, a bracket rigidly secured to said casing below said barrel and provided within said barrel with a tubular guide sleeve for the rear end of said plunger, a spring-pressed sear lever pivoted to said casing and having one end engageable with the detent of said plunger to hold the same retracted, a trigger pivoted within said casing and operative on said sear lever to release the same and produce the firing action, said trigger having an upwardly projecting lug operative on said sear lever, said barrel being cut away or removed at that portion thereof that overlies said trigger lug when said barrel is in the forward position, the lower uncut or removed body portion of said tube being arranged to overlie said lug and prevent firing when said barrel is in a rearward position, said trigger lug being an L-shaped structure, the base of which engages the end of said sear lever and the upwardly projected portion of which works through an opening in said sear lever.

3. In a gun of the kind described, a casing, a

barrel slidably mounted in said casing, ejecting mechanism in said barrel including a rearwardly projecting rod terminating in the detent, means for yieldingly projecting said ejecting mechanism forward when released, and means for holding said ejecting mechanism retracted and for releasing the same, comprising a bracket that is independent of but secured to said casing, a spring-pressed sear pivoted to said bracket and operative on the detent of said rod to hold said ejecting mechanism retracted, and a trigger also pivoted to said bracket and operative on said sear to retract the same and release the ejecting mechanism, and which trigger has an approximately L-shaped lug for action on said sear, and which barrel is provided with a stop surface which, when the barrel is rearward, overlies the lug of said trigger and holds the same against sear-retracting action, but which stop surface, when said barrel is forward, clears the lug of said trigger for firing action.

4. In a gun of the kind described, a casing, a barrel slidably mounted in said casing, ejecting mechanism in said barrel including a rearwardly projecting rod terminating in the detent, means for yieldingly projecting said ejecting mechanism forward when released, and means for holding said ejecting mechanism retracted and for releasing the same, comprising a bracket that is independent of but secured to said casing, a spring-pressed sear rod to hold said ejecting mechanism retracted, and a trigger also pivoted to said bracket and operative on said sear to retract the same and release the ejecting mechanism, said bracket having an upwardly extended portion terminating in a guide tube located within said barrel and serving to guide the detent equipped rod of said ejecting mechanism, and which trigger has an approximately L-shaped lug for action on said sear and which barrel is provided with a stop surface which, when the barrel is rearward, overlies the lug of said trigger and holds the same against sear-retracting action, but which stop surface, when said barrel is forward, clears the lug of said trigger for firing action.

JAMES P. APPLEBY.
